(57) **CLAIM**

The ornamental design for a oil tank for transmission fluid filter, as shown and described.

DESCRIPTION

FIG. 1 is a top perspective view of the oil tank for transmission fluid filter, particularly showing the inventive design thereof;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof; and,

FIG. 7 is a front elevation view thereof.
